UNITED STATES PATENT OFFICE.

WILLIAM WOLFE, OF ST. LOUIS, MISSOURI.

NAILING MECHANISM FOR HEEL-BUILDING MACHINES.

1,115,998.

Specification of Letters Patent.

Patented Nov. 3, 1914.

Application filed February 12, 1912. Serial No. 677,040.

To all whom it may concern:

Be it known that I, WILLIAM WOLFE, a citizen of the United States, residing in the city of St. Louis and State of Missouri, have 5 invented new and useful Improvements in Nailing Mechanism for Heel-Building Machines, of which the following is a specification.

This invention relates to improvements 10 in heel building machines, and has special reference to a novel construction and operation of nailing mechanism, operating in timed relation with a heel-forming mechanism to successively supply the nails and 15 drive them into the heel.

The invention is concerned with novel means for continuously supplying nails; with novel means for delivering the nails so supplied to a carrier; and with mechanism 20 for driving the nails into the heel, certain of these features constituting, so to speak, independent subjects of invention, while others serve as elements in novel combinations including such independent features.

25 In carrying out my invention I employ a nail reservoir and means for agitating the same which operates to deliver a continuous supply of nails to a plurality of slots in an inclined race-way. At the foot of this race-way the nails are successively delivered to a temporary holder, and at a certain period of the operation of the machine the nails are forced from this holder and permitted to descend through chutes into a carrier associated with a reciprocating part of the 35 heel-forming mechanism. At the proper time such carrier is brought into position over the heel and the nail-driving mechanism is operated to force the nails from the carrier into the heel.

All of the operations described are performed automatically, the machine being of the type in which motion is automatically arrested after each reciprocation of the heel-forming mechanism, to be again set in motion at the will of the operator.

The machine illustrated herein is of the same general character as to construction and mode of operation as that forming the 45 subject-matter of a pending application filed by me January 3rd, 1911, Ser. No. 600,611.

As the present invention is concerned only with the nailing mechanism, I will refer only briefly to those parts which are not directly involved in the present invention, but

which are fully described in my said pending application.

In the accompanying drawings—Figure 1 is a view in front elevation of a machine constructed according to my invention; Fig. 2 is a view in side elevation of the same; Fig. 3 is a sectional view of the driving mechanism, the section being taken on the line 3—3 of Fig. 2; Fig. 4 is a plan view, on an enlarged scale, partly broken away, 60 of the nail magazine and chute, together with certain adjunctive parts for releasing the nails; Fig. 5 is a longitudinal sectional view taken on the line 5—5 of Fig. 4; Fig. 6 is a view in end elevation and partly in 65 section, on an enlarged scale, of the nail-releasing mechanism; Fig. 7 is a sectional view on the line 7—7 of Fig. 6; Fig. 8 is a cross section on the line 8—8 of Fig. 6, illustrating one of the nail-controlling plates; Fig. 9 is a view in rear elevation of a portion of the nail-releasing bar showing the manner of mounting the nail-releasing 70 plates therein; Fig. 10 is a plan view, on an enlarged scale, showing the construction of 75 parts at the foot of the race-way; Fig. 11 is a similar view on a larger scale, and partly in section, showing one of the spring-controlled nail-holding members; Fig. 12 is a plan view of the combined press-block and 80 nail-holder or carrier; and Fig. 13 is a section on the line 13—13 of Fig. 12.

Referring now to the drawings, the numeral 1 indicates the standard of the machine on which is mounted an upper framework 2, supporting or housing the major portion of the operating mechanism. Mounted in bearings in the frame 2 is a main shaft 3 which is driven from a pulley 4 through the medium of a clutch 5. The pulley 4 will be driven by a suitable belt, which, however, is not shown in the drawings. Secured on the shaft 3 to rotate therewith are two cams 6 and 7. Pivotedly mounted at 8 in the frame centrally of its upper end is a rocker arm 9, which has mounted in opposite sides at its top two anti-friction rollers 10, 11, which are adapted to be alternately engaged by the cams 6 and 7 to rock the lower end of the arm 9 95 backward and forward. Pivotedly secured to the lower end of the rocker arm 9 is one end of a link 12 which, at its other end, is pivotally secured to a ram 13 slidably mounted in the frame. This ram carries at 100 105 110

its forward end a combined press-block and nail-holder 14 which is shown in detail in Figs. 12 and 13. As clearly described and shown in my pending application, this combined press-block and nail-holder is capable of vertical movement in an extension 15 forming the end of the ram 13, and is normally held upward by a spring incased in said extension. The press-block 14 is provided preferably with four vertical apertures, one of said apertures, 16, being located at the center, and the other three apertures, 17, being located near the circumference of the press-block in such manner as to form the points of an imaginary isosceles triangle.

18 indicates spring arms which are secured at one end in the wall of the press-block, and have their free ends bent to extend into the apertures 16 and 17. The purpose of these spring arms is to retain nails, such as 19, in their respective apertures until such time as said nails are driven into the compiled lifts. Secured on the frame 2 is a bracket 20 which supports the upper end of a race-way 21, shown in detail in Figs. 4, 5, 10 and 11. Pivotal mounted at 22 at the upper end of this race-way is a nail box 23 having a removable, hinge-connected lid 24 and end 24^a normally locked in position by a spring catch 25. The bottom of the nail box 23 is provided with three longitudinally-extending V-shaped grooves 26 which are of a size to permit the shanks of the nails to fall freely therethrough but to retain the heads of the nails which are received in said V-shaped grooves so that they lie substantially flush with the upper surface of the bottom of the nail box. Secured on the sides of the box toward its lower end is a clip 27 to which is pivotally secured the upper end of a hanger 28. Pivotally connected to the lower end of this hanger is a rod 29 which is pivotally connected at its lower end, as indicated at 30, to a crank disk 31 near the periphery of the latter. This crank disk is mounted on the end of a shaft 32 which is supported near opposite ends in bearings 33 provided at the ends of a casting 33^a bolted on the frame of the machine. On the opposite end of the shaft 32 is mounted a sprocket wheel 34 which is driven by a sprocket chain 35. This sprocket chain is driven from a small sprocket wheel 36 fast on a stub shaft 37 which is mounted at its inner ends in bearings (not shown) in the frame of the machine. On the hub of the pulley 4 there is mounted a sprocket wheel 38, and on the end of a shaft 39, shown only in section, in Fig. 3, there is mounted a sprocket wheel 40. A sprocket chain 41 passes over the two sprocket wheels 38 and 40. Mounted on the shaft 37 is a large sprocket wheel 42 which is so located

as to have its teeth engaged by the outer side of the sprocket chain 41. The chain 35 passes over the small sprocket wheel 36, engages one side of the sprocket wheel 34, and then passes over a small sprocket wheel 43, which is fast on the end of a shaft 44 mounted in bearings 45 on the side of the frame 2. The shaft 39, above referred to, is similarly mounted on the opposite side of the machine, and these shafts 44 and 39 operate the two paste-applying devices, indicated, respectively, by the numerals 46 and 47, through the medium of a sprocket drive 48 and gears 49 and 50. As the paste-applying device forms the subject-matter of a separate application it need not be described herein more in detail. As the shaft 32 is revolved through the driving mechanism shown more clearly in Fig. 3, the crank disk 31 will operate to raise and lower the rod 29, which, in turn, causes an up and down movement or reciprocation of the nail box 23 on the pivot 22. This movement of the nail box 23 causes the nails therein to be agitated and to fall into the slots 26, in which they slide downwardly and enter corresponding slots 51 formed in the race-way 21. Mounted on the upper side of the race-way 21 to extend parallel therewith, and at a slight distance above the heads of the nails in the slots of said race-way, is a plate 52 secured in position by screws 53, the purpose of which is to prevent the nails from riding up on each other and thus choking the feed. The lower end of the race-way 21 is supported on and connected by means of screws 53^a to a nail support 54, which is provided at the upper end of a bracket arm 55 secured on the side of the frame 2. The nail support 54 is provided with an upwardly curved portion 56 provided with slots 57 which form continuations of the slots 51, and which curved portion merges into a horizontal portion 58 of the nail support provided with three apertures 59 which are entered by the slots 57. Each aperture 59 with its slot 57 is preferably provided in a block 60, which blocks are inserted in grooves formed in the nail support 54 and secured in position by means of screws 61. Referring to Fig. 11, each of the blocks 60 is bored through from one side to provide a recess 62 having a restricted opening communicating with the aperture 59, which opening permits a metal ball 63 to project part way into the aperture 59, said ball being normally held in such position by means of a spring 64 engaged by a screw 65 which likewise closes the outer opening of the recess 62. Secured on the under side of the nail support 54, and forming continuations of the apertures 59, are three tubes 66 having in their rear sides slots 67, said tubes being held in position by means of binding pins 68 mounted in re-

- cesses in the horizontal part of the nail support 54 and pressed inward against said tubes by means of set screws 69. Adjustably secured on each tube 66 by means of a set screw 70 is a sleeve 71 carrying at its lower end a nail tube 72, the lower ends of said nail tubes terminating above and immediately over the apertures 17 in the press-block and nail-holder 14. As the nails slide down the race-way 21 they successively enter the apertures 59, being retained therein by the balls 63. The mechanism for releasing these nails so as to permit them to fall through the nail tubes 72 into the combined press-block and nail-holder 14 will now be described.
- Secured on the side of the nail support 54 by means of a screw 73 is a bracket arm 74 having a horizontal portion 75 extending over and parallel with the upper surface of the nail support and having an upward extension 76 at its outer end, in which is pivotally mounted at 77 one end of a lever 78 having its outer end portion bent downward and outward to provide an engaging end 79 which is adapted to be actuated by a lug 80 provided on the hub 81 of a crank disk 82 mounted on the main shaft 3. Mounted in the horizontal portion 75 of the bracket 74 are three plungers 83, each of which has secured thereon a disk 84 by means of which it is pressed normally upward by a spring 85 seated in a recess 86, the disk 84 bearing against an apertured plate 87 secured on the upper side of the member 75, and through which the upper ends of the plungers 83 project. The said plungers have their lower ends located immediately over and slightly above the apertures 59 in the nail support.
- The lever 78 is provided on its under side with three dove-tailed grooves, in each of which is inserted the lower member 88 of an L-shaped key, said lower portion being provided with an aperture 89, and the upright portion 90 having secured therein one end of a pin 91 which is slidably mounted in the lever 78 and is held against withdrawal by a cotter-pin, or the like, 92. A spring 93 surrounding the pin 91, and located between the side of the lever 78 and the upright portion 90 of the key, tends normally to maintain said upright portion at a distance from the side of the lever. The under side of said lever is provided with a recess 94 with which the aperture 89 may be brought to register when the key is pressed inward. A guide-pin 78^a is provided for the lever, and a spring 79^a holds said lever normally in a raised position.
- In the operation of the machine, as the nails fed down the race-way rest in the apertures 59 the rotation of the shaft 3 causes the lug 80 to engage the end 79 of the lever 78, thereby throwing said lever downward and causing the under sides of the keys to strike

the upper ends of the plungers 83 and press them downward. As this occurs the lower ends of said plungers strike the heads of the nails in the apertures 59 and press them past the balls 63 which are thereby moved inward 70 against resistance of the springs 64. It sometimes occurs, however, that one or more of the nails will fail to feed, and it is then necessary to operate the machine again so that the missing nail may be supplied and 75 driven into the heel. To accomplish this the operator presses in the keys controlling the plungers of the tubes through which nails have been fed, and on placing the machine in operation only the plunger of the tube 80 which did not supply the nail will be operated. Assuming, for illustration, that nails have been supplied through the two tubes at the right of Fig. 6, and that no nail had fallen through the tube at the extreme 85 left; the operator would then press in the keys controlling the plungers of the two right-hand tubes and place the machine in operation. As the lever 78 descends the two plungers 83 at the right will simply pass 90 through the apparatus 89 and into the recesses 94 of the lever and will not be operated, while the imperforate part of the key at the left will engage its plunger and cause it to descend and release the nail held in the aperture 59 beneath it. The nails released from the nail-holder 54 fall through the nail tubes 72 and into the apertures 17 of the combined press-block and nail-holder 14. As the ram 13 is thrown outward by the operation of the 100 cam 6 the heel-former (not herein described) and the press-block carrying the nails are moved forward to the lifts, said press-block being immediately over them. At such time the crank disk 82, through the medium of a 105 pitman rod 95 pivotally connected to said crank disk at one end, as indicated at 96, and at its other end to a drive bar 97, indicated at 98, carries the said drive bar downward whereby drivers 99, secured in the 110 lower end thereof, will enter the apertures 17 and force the nails therein into the heel lifts, and at the same time the lower end of the drive bar engages the press-block and forces it downward on the heel lifts to compress the latter. In building heels of pieced lifts it is usual to employ three nails. Where whole lifts are used but a single nail may be required. Where this is the case it will be understood that a single tube 72 115 120 would be employed, having its lower end terminating immediately over the central aperture 16 of the press-block and only one of the slots of the race-way would be utilized.

The clutch mechanism 100 (Fig. 2) actuated by the operator by means of the rod 101, need not be specifically described herein, as it forms no part of the invention, and a similar clutch being fully described and 130

illustrated in my said pending application. It is sufficient to say that the operator presses upon a treadle to draw down the rod 101 which throws the clutch 5 into operation, 5 and at the expiration of a complete revolution of the shaft, resulting in a single reciprocation of the ram 13, the clutch is automatically thrown out of operation and the machine stopped. In such movement the 10 drive bar 97 will have been lowered and raised.

Referring now particularly to Fig. 7, the slot 67 in the tubes 66 is for the purpose of permitting the shank of the nail to enter 15 said tube as the head passes into the aperture 59. In the event that nails too long to pass by the upper edge of the sleeve 71 should be employed, the set screw 70 would be loosened and the sleeve 71 lowered on the tube 76 to 20 permit the free entrance of the shank of such nail through the slot 67.

I claim:

1. In a heel building machine, heel nail-ing mechanism involving an inclined race-way provided with slots, means for continuously supplying nails to the slots of said race-way, a nail support at the bottom of said race-way, nail tubes leading therefrom, a horizontally reciprocable nail holder 25 movable by the machine to a position under said tubes, and means operated from the machine for releasing the nails from said support in timed relation with the movement of said nail holder.

2. In a heel building machine, heel nail-ing mechanism involving an inclined slotted race-way, means for continuously supplying nails to said race-way, a nail support at the foot of said race-way, a series of spring- 40 controlled plungers co-operating with said support, nail tubes leading from said support, a horizontally reciprocable nail holder movable by the machine to a position under said tubes, and means actuated from the machine for depressing said plungers to release the nails from said support at timed intervals relative to the movement of the nail holder.

3. In a heel building machine, in combination with a reciprocating nail-holder, an inclined slotted race-way, means for supplying nails thereto, a nail-support at the foot of said race-way having apertures, nail tubes leading from said apertures and 55 adapted to deliver nails to said nail-holder, a spring-pressed member projecting into each of said apertures and adapted to support the head of a nail, a series of spring-controlled plungers mounted immediately over said apertures, and means operated from the machine for depressing said plungers to force the nail heads past said members.

4. In a heel building machine, nail-driv-ing mechanism comprising a support pro-

vided with means for releasably holding nails therein, spring-controlled plungers mounted above said support and adapted to force the nails therefrom, a movable member for depressing said plungers, and means 70 carried by said member and adapted to be actuated by the operator to render inoperative any selected number of said plungers in the operation of said member.

5. In a heel building machine, nail-driv-ing mechanism comprising a support pro- 75 vided with means for releasably holding nails, a series of spring-controlled plungers mounted above said support, a depressible member for actuating said plungers to cause 80 them to engage the nails and force them out of said holder, said member being provided in its bottom with recesses in line with the upper ends of said plungers, and a series of movable keys carried by said member and 85 provided with imperforate portions for engaging said plungers and with apertures which, by moving said keys, may be brought into alinement with said recesses whereby when any one of said keys is so moved the 90 upper end of said plunger will enter said aperture and recess and will not be actuated in the operation of said member.

6. In a heel building machine, nail-driv-ing mechanism comprising a support pro- 95 vided with means for releasably holding a series of nails, a series of spring-controlled plungers mounted above said support, a de- 100 pressible member adapted to engage said plungers to force them into engagement with the nails whereby to release the latter, means operated by the machine for actuating said member, and a series of spring-con- 105 trolled keys mounted on said member and adapted to be moved by the operator to ren- der a selected number of said plungers inoperative in the movement of said depressible member.

7. In a heel building machine, nail-driv-ing mechanism comprising a support pro- 110 vided with means for releasably holding nails therein, a series of spring-controlled plungers mounted above said support, a 115 spring-supported lever pivotally mounted at one end above said plungers, and means op- 120 erated by the machine for engaging the free end of said lever to depress the same whereby to push said plungers downward and cause them to engage and force the nails out of said holder.

8. In a heel building machine, nail-driv-ing mechanism comprising a support pro- 125 vided with means for releasably holding nails therein, a series of spring-controlled plungers mounted above said support, a spring-supported lever pivotally mounted at one end above said plungers, a crank disk, and a lug on said crank disk adapted in the revolution of the latter to engage the free end of said lever to depress the same where- 130

by to cause said plungers to be pushed downward to engage the nails and release them from said support.

9. In a heel building machine, nailing mechanism comprising a nail-support having apertures provided with means for releasably holding nails therein, tubes supported beneath said apertures, each of said tubes having a slot in its side, and nail

chutes having sleeves adjustably mounted 10 on the respective tubes.

In testimony whereof, I have hereunto set my hand in presence of two subscribing witnesses.

WILLIAM WOLFE.
